(57) **CLAIM**

We claim the ornamental design for a processing apparatus and cover combination, as shown and described.

DESCRIPTION

FIG. 1 is a perspective view of a processing apparatus and cover combination showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a back view thereof;

FIG. 8 is the perspective view of the combination of the processing apparatus having the cover thereover of FIG. 1;

FIG. 9 is the right side view of FIG. 8, the left side view being identical;

FIG. 10 is the front view of FIG. 8, the back view being identical;

FIG. 11 is the top view of FIG. 8; and,

FIG. 12 is the bottom view of FIG. 8.
